UNITED STATES PATENT OFFICE.

FRANZ A. FULLER, OF NEWARK, NEW JERSEY.

MATCH-BOX.

1,376,931.

Specification of Letters Patent.

Patented May 3, 1921.

Application filed August 26, 1918. Serial No. 251,491.

To all whom it may concern:

Be it known that I, FRANZ A. FULLER, a citizen of the United States, residing in the city of Newark, in the county of Essex and 5 State of New Jersey, have invented certain new and useful Improvements in Match-Boxes, of which the following is a full, clear, and exact description, such as will enable others skilled in the art to which it pertains 10 to make, construct, and use the same, reference being had to the accompanying drawings, and to letters of reference marked thereon, forming a part of this specification.

The present invention has reference to 15 improvements in that class of match boxes, especially adapted to receive telescoping wooden boxes containing safety matches, and the object thereof, is to so construct the box that it will entirely inclose the box containing the safety matches, in order that the match box which in practice, is provided 20 with friction material upon its side suitable for scratching matches thereon, for the purpose of igniting them, may at all times be 25 kept dry and moisture-proof.

A further object of my present invention is to provide a lid or cover which, when the box is opened, will furnish an effective wind shield which will assist in preventing the 30 matches from being extinguished after the same have been ignited upon the friction material arranged upon the side of the telescoping wooden match box.

The invention consists therefore, in the 35 novel construction of the match box herein-after set forth, and furthermore, the invention consists in the various novel arrangements and combinations of the parts, as well as in the details of the construction thereof, 40 all of which is fully described in the following specification, and then finally embodied in the clauses of the claim.

The preferred embodiment of my invention is clearly indicated in the accompanying 45 drawings, in which—

Figure 1 represents a perspective view of the box.

Fig. 2 represents a perspective view of the same open, illustrating a portion of a telescoping wooden box designed to receive 50 safety matches, secured therein.

Fig. 3 represents a rear side elevation of the box, and

Fig. 4 represents on an enlarged scale a 55 transverse sectional end view taken on line

x—x in Fig. 1 looking in the direction indicated by the arrow.

Similar letters of reference are employed in all of the above described views to indicate corresponding parts throughout the 60 drawings and specification.

The improved match box is preferably made of flexible sheet metal of any suitable kind, such as brass, tin, copper or aluminum. The body portion of the box comprises a 65 back portion *a*, and a turned-up side portion *b*, the edge of the side portion *b* being curled inwardly to form a tubular bearing *c*. The body portion of the box is further provided with a turned-up lip *d* so as to partly overlie the front side of the telescoping wooden box *e* containing the safety matches. The body portion *a* at each end is further provided with turned-up end lips *e* and *f* which together with the turned-up lip *d* and side 70 portion *b* provide means for properly and securely positioning the box *e* containing the safety matches upon the body portion *a* of the match box, in order to prevent accidental separation of the same. The body 75 portion of the box, comprising the back portion *a*, turned-up side portion *b*, turned-up lips *d*, *e*, and *f*, preferably consists of a single piece of metal cut to proper shape and bent into the form shown in the drawings. 80 The lid of the box comprises a top portion *g*, a front portion *h*, and side portions *i*—*i*, and also preferably consists of a single piece of metal cut to proper shape, and bent into the form shown in the drawings. 85 The lid of the box comprises a top portion *g*, a front portion *h*, and side portions *i*—*i*, and also preferably consists of a single piece of metal cut to proper shape, and bent into the form shown in the drawings. 90

The rear edge of the top portion *g*, of the lid is bent downwardly as at *j* (see Fig. 4 of the drawings) designed to engage with the turned-up side portion *b* of the body portion of the box, in order to limit the upward movement of 95 the lid, as clearly indicated in Fig. 2 of the drawings. Each side portion *i*—*i* of the lid is provided with an apertured ear *k* for the reception of the headed studs *l*—*l*, which enter and are received by the tubular bearing *c*, and by means of which the lid is pivotally secured to the body portion of the box. 100

The body portion of the box and the lid are of such shape as to lend themselves readily to manufacture by the use of suitable punches and dies, from ordinary sheet metal, and that when assembled, the possibility of the parts becoming separated by careless manipulation have been reduced to a minimum. Means are also provided on 110

the back portion *a* of the body of the box for limiting the downward movement of the lid, said means consisting of lugs *m* formed integrally with the back portion *a* and 5 which engage with the side portions *i*—*i* of the lid. The turned-up lip *d* of the body portion of the box, preferably near its ends is provided with a pair of inwardly extending projections *n* formed by forcing the 10 metal of the said lip *d* inwardly so as to provide means for pressing against the side of the match box *e*, to firmly secure the same upon the body portion of the box. Said lip *d* is further provided with outwardly extending 15 projections *o*, also formed by forcing the metal of said lip *d* outwardly, designed to engage with a portion of the bead *p* formed in the front portion *h* of the lid, at *g*.

These outwardly extending projections *o* 20 engaging with the inside of the bead *p* cause the lid *g* to engage with the body of the box, and to come together with a pronounced snap, thereby locking the two box sections together. The turned-up lip *d* is further 25 provided with a raised portion *r* corresponding to the raised portion *s* formed on the front portion *h* of the lid, which raised portions form means to be engaged by the fingers of the user to open the box. Similar 30 raised portions *t* are formed on the side portions *i*—*i* for the same purpose.

Experience has demonstrated that the organization above described is a highly efficient one, and while I have shown the preferred embodiment of my present invention, I do not wish to be limited to the exact details of construction shown and described, as obvious modifications thereof, not involving the exercise of invention, may be 40 made by any skilled mechanic, and such departures from what is herein set forth, I consider within the scope and terms of my claims.

I claim:—

45 1. A match box comprising a box body and a hinged lid, said box body adapted to hold a box of safety matches, and comprising a back portion to receive the box of matches, a turned-up side portion provided 50 with a bearing extending lengthwise thereof, and a turned-up front lip and two end lips extending from said back portion for positioning and holding said box of matches upon the back portion, said hinged lid comprising a top portion, a cut away front portion and two side portions extending from 55 said top portion, the front and side portions of the lid overlying the turned-up front lip and end lips of the back portion of the box 60 body, lugs formed integrally with said back portion of the box body to be engaged by the side portions of the lid to limit the downward movement of said lid, and means formed on the turned-up front lip of the 65 back portion of the box body designed

to have holding engagement with means formed on the front portion of the lid for locking the box body and lid together.

2. A match box comprising a box body and a hinged lid, said box body adapted to 70 hold a box of safety matches, and comprising a back portion to receive the box of matches, a turned-up side portion provided with a bearing extending lengthwise thereof, and a turned-up front lip and two end 75 lips extending from said back portion for positioning and holding said box of matches upon the back portion, said hinged lid comprising a top portion, a cut away front portion and two side portions extending from 80 said top portion, the front and side portions of the lid overlying the turned-up front lip and end lips of the back portion of the box body, lugs formed integrally with said back portion of the box body to be engaged by the 85 side portions of the lid to limit the downward movement of said lid, means formed on the turned-up front lip of the back portion of the box body designed to have holding engagement with means formed on the front portion of the lid for locking the box body and lid together, and a raised portion formed on the cut away front portion of the lid, and a similarly raised portion formed on the front lip of the back portion of the 90 box body adapted to be engaged for opening the box.

3. A match box comprising a box body and a hinged lid, said box body adapted to 100 hold a box of safety matches, and comprising a back portion to receive the box of matches, a turned-up side portion provided with a bearing extending lengthwise thereof, and a turned-up front lip and two end 105 lips extending from said back portion for positioning and holding said box of matches upon the back portion, said hinged lid comprising a top portion, the rear edge of which is bent downwardly designed to engage with the turned-up side portion of the body portion of the box in order to limit the upward 110 movement of the lid, a cut away front portion and two side portions extending from said top portion, the front and side portions of the lid overlying the turned-up front lip and end lips of the back portion of the box body, lugs formed integrally with said back portion of the box body to be engaged by the side portions of the lid to limit the downward movement of said lid, and means formed on the turned-up front lip of the back portion of the box body designed to have holding engagement with means formed on the front portion of the lid for locking the box body and lid together.

4. A match box comprising a box body and a hinged lid, said box body adapted to 115 hold a box of safety matches, and comprising a back portion to receive the box of matches, a turned-up side portion provided 120

with a bearing extending lengthwise thereof, and a turned-up front lip and two end lips extending from said back portion for positioning and holding said box of matches
5 upon the back portion, said lid comprising a top portion, provided with integral means for limiting the upward movement of said lid, a cut away front portion and two side portions extending from said top portion,
10 the front and side portions of the lid overlying the turned-up front lip and end lips of the back portion of the box body, lugs formed integrally with said back portion of the box body to be engaged by the side portions of the lid to limit the downward movement of said lid, means formed on the

turned-up front lip of the back portion of the box body designed to have holding engagement with means formed on the front portion of the lid for locking the box body 20 and lid together, and integral means formed on the front portion of the lid, and integral means formed on the front lip of the back portion of the box body adapted to be engaged for opening the box. 25

This specification signed and witnessed this 22d day of August, 1918.
